(57) **CLAIM**

The ornamental design for a disc golf marker, as shown and described.

DESCRIPTION

FIG. 1 is a top perspective view of a disc golf marker showing my new design;

FIG. 2 is a bottom perspective view of the disc golf marker;

FIG. 3 is a front elevational view of the marker;

FIG. 4 is a real elevational view of the marker;

FIG. 5 is a left side elevational view of the marker;

FIG. 6 is a right side elevational view of the marker;

FIG. 7 is a top plan view of the marker;

FIG. 8 is a bottom plan view of the marker; and,

FIG. 9 is an exploded perspective view of the marker showing the broken line of the measuring rule housing is included for the purpose of illustration and forms no part of the claim design.
